US00D786232S

(12) **United States Design Patent** (10) **Patent No.:** **US D786,232 S**
(45) **Date of Patent:** **** May 9, 2017**

(54) **CASE FOR ELECTRONIC DEVICE**

(71) Applicant: **SPIGEN KOREA CO, LTD.**, Seoul (KR)

(72) Inventors: **Dae-Young Kim**, Seoul (KR); **Soo Ha Jung**, Seoul (KR)

(73) Assignee: **SPIGEN KOREA CO., LTD.**, Geumcheon-Gu, Seoul (KR)

(**) Term: **15 Years**

(21) Appl. No.: **29/567,539**

(22) Filed: **Jun. 9, 2016**

Related U.S. Application Data

(63) Continuation of application No. 29/497,432, filed on Jul. 24, 2014, now Pat. No. Des. 775,614.

(57) **CLAIM**

The ornamental design for a case for electronic device, as shown and described.

DESCRIPTION

FIG. 1 is a front perspective view of a case for electronic device, having inner portion and outer portion, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded front perspective view thereof showing the inner and outer portions of the case for electronic device separated for clarity of disclosure;

FIG. 10 is an exploded rear perspective view thereof;

FIG. 11 is a front perspective view showing only the inner portion of the case for electronic device for clarity of disclosure;

FIG. 12 is a rear perspective view thereof;

FIG. 13 is a front perspective view showing only the outer portion of the case for electronic device for clarity of disclosure; and,

FIG. 14 is a rear perspective view thereof.

The broken lines depict unclaimed environment and form no part of the claimed design.

1 Claim, 14 Drawing Sheets
